(57) **CLAIM**

The ornamental design for a sign, as shown and described.

DESCRIPTION

FIG. 1 is a perspective view of the a first embodiment of a sign showing our new design;

FIG. 2 is a front elevational view thereof;

FIG. 3 is a back elevational view thereof;

FIG. 4 is a right-side elevational view thereof, the left-side elevational view being a mirror image thereof;

FIG. 5 is a bottom plan view thereof;

FIG. 6 is a top plan view thereof;

FIG. 7 is a front elevational view of a second embodiment;

FIG. 8 is a front elevational view of a third embodiment;

FIG. 9 is a front elevational view of a fourth embodiment;

FIG. 10 is a front elevational view of a fifth embodiment;

FIG. 11 is a front elevational view of a sixth embodiment;

FIG. 12 is a front elevational view of a seventh embodiment;

FIG. 13 is a front elevational view of an eighth embodiment;

FIG. 14 is a front elevational view of a ninth embodiment; and,

FIG. 15 is a front elevational view of a tenth embodiment.

The back elevational view, the right-side elevational view, the left-side elevational view, the bottom plan view, and the top plan view of the second, third, fourth, fifth, sixth, seventh, eighth, ninth, and tenth embodiments are the same as the first embodiment's views shown in FIGS. 3-6.
